UNITED STATES PATENT OFFICE

2,228,609

SILO FOR THE STORAGE OF GRAIN AND
THE LIKE

José Ragni, Buenos Aires, Argentina

Application February 10, 1939, Serial No. 255,753
In Argentina February 25, 1938

3 Claims. (Cl. 189—3)

This invention relates to an improved construction of silo or store for the storage of grain or similar granular or pulverulent materials in general and substantially has for object an improved silo or store which owing to its particular features of construction and arrangement, offers considerable advantages over the structures or systems heretofore proposed and used for said purposes.

10 A substantial feature of the improved construction of silo or store forming the object of this invention consists in that the same comprises two or more container units, each formed by two hollow body parts of a particular rounded or polyhedral shape, with their outer walls joined at their bases, being provided with means for loading or filling the material to be stored into said container units and for discharging the same, as well as with means for supporting the 15 containers at a suitable height from the ground.

Generally speaking, the said hollow body parts may conveniently be constructed of conical, or pyramidal shape, either truncated or not.

By means of this particular arrangement it 25 will be possible to obtain, for a silo or store of a certain capacity, a much larger area for aerating purposes than that which is provided in silos or storage structure, of cylindrical or spherical shape.

30 At the same time, the construction in accordance with this invention allows of using for a silo of any desired capacity, a structure of much less height than that required by the known cylindrical silos, which, besides the advantage of providing a larger area for aeration purposes, assures an efficient ventilation of the material or goods stored in the container, owing to the increased space exposed to air, while the reduced height of the lower or bottom layers of the goods, permits of maintaining the same in a loose condition, thereby establishing most favorable conditions for storing all kinds of pulverulent materials in general.

45 The invention also views other objects which will be set forth in the course of the following specification.

In order that the invention may be readily understood and carried into practice, a preferred 50 form of construction of the same has been shown in the accompanying illustrative drawing, in which:

Figure 1 shows a front elevation of one of the 55 container units which constitute the improved silo or storage structure.

Figure 2 illustrates an elevation of another embodiment of a unit of the improved silo.

Figure 3 represents a plan view showing the manner of arranging a series or set of container units according to Figure 1, so as to form a 5 multiple or combined silo, and

Figure 4, finally, indicates the manner of combining the elements when shaped as shown in Figure 2.

In all the said views, the same numbers of 10 reference have been used to indicate like or corresponding parts.

The novel type of silo in accordance with this invention consists, as already stated, of one or several container units, each of which is formed 15 by two hollow body parts or sections 1 and 2, of suitable form and dimensions, conveniently connected together at their base ends, so as to form a container of varying capacity. In Figure 1, for instance, the parts 1 and 2 of the container 20 form each a hollow right circular cone, the walls of said cones being connected together at their common base 3, with the axes of both cones extending in a vertical direction.

According to the modified construction shown 25 in Figure 2, the said hollow body parts 1 and 2 have been arranged on a horizontal axis, with their bases 3 placed and joined along a vertical plane.

The container units just described will 30 preferably be arranged at a certain level above the ground, in order to facilitate their discharge and to that end they will be provided with a suitable supporting frame, such as the structure 5, conveniently formed of metal and provided with 35 reinforcing means for securing the necessary rigidity. The upper and lower parts or halves of said container units will respectively be provided at their apices with a port 6 for loading or filling the same, and with an outlet port 7, 40 provided with a slide or similar controlling device, for the discharge of the materials into a carrier vehicle.

For the construction of the body parts 1 and 2, 45 suitable sheet metal, either plain or corrugated, may be used and adequate reinforcing means for counteracting the pressure of the goods contained in said units may be applied thereto.

In order to provide a storage structure or silo 50 of large capacity, the container units may conveniently be arranged in series or sets, sufficient in number to supply the capacity required, after the manner illustrated by way of example in Figures 3 and 4; in the former, the set includes four container units of the type shown in Fig. 1, 55

preferably arranged around a single elevating device 8, to be used indifferently for charging or filling each of said units by means of the feed pipes 9; it will be understood that loading or filling may be performed in series or separately, as may be desired.

In the arrangement shown in Figure 4, eight container units according to the type shown in Figure 2, have been combined in a set, all of them being fed by means of a single elevator device 8, from which extend the pipes 9 for the separate or conjoint feeding of said units.

From the foregoing description, the manner of operating of the device will be readily understood by those skilled in the art, so that a detailed explanation of the same has been deemed unnecessary.

Although in the foregoing specification the several container units are described as being supported at a certain level above the ground, it will be evident that, without departing from this invention, the lower part of the containers might be placed at a level with the ground, or even below the same, and the upper part of the container might serve as a cover or hood therefor, as has been explained before.

It will further be evident that several modifications of construction and detail might be introduced without departing from the scope of this invention, as particularly set forth in the claims hereto annexed.

Having now clearly described and ascertained the nature of my said invention and in what

manner the same is to be performed, I declare that what I claim and desire to secure by Letters Patent, is:

1. In a silo, a pair of shallow shell members formed as nappes of right circular cones of the same diameter and having a relatively large apex angle and being mounted with their bases coincident, and means for mounting said shell members with their axes coincident and vertical, said shell members being respectively provided at their apices with an inlet port and an outlet port.

2. In a silo, a pair of shallow shell members formed as nappes of right circular cones of the same diameter and having a relatively large apex angle and being mounted with their bases coincident, and means for mounting said shell members with their axes coincident, the assembly of said shell members being provided at the uppermost and lowermost points thereof respectively with an inlet port and an outlet port.

3. In a silo, a pair of shallow shell members formed as nappes of right circular cones of the same diameter and having a relatively large apex angle and being mounted with their bases coincident, and means for mounting said shell members with their axes coincident and horizontal, the assembly of said shell members being provided at the uppermost and lowermost points thereof respectively with an inlet port and an outlet port.

JOSÉ RAGNI.
